US00D522656S

(12) **United States Design Patent** (10) **Patent No.:** **US D522,656 S**
Orr et al. (45) **Date of Patent:** **** Jun. 6, 2006**

(54) **ANALYTE TEST METER**

(75) Inventors: **Allan Orr**, Westhill (GB); **Marc Daniel Stern**, Oakland, CA (US); **Steven Alexander Syme**, Inverness (GB); **Wayne Kvenvold**, Sunnyvale, CA (US); **Thomas Rangi Sutton**, Milan (IT); **Adelio Enzo Alfiero Bolognesi**, Rovello Porro (IT)

(73) Assignee: **Lifescan Scotland Limited** (GB)

(**) Term: **14 Years**

(21) Appl. No.: **29/220,412**

(22) Filed: **Dec. 29, 2004**

(51) **LOC (8) Cl. 24-02**

(52) **U.S. Cl. D24/169; D10/81**

(58) **Field of Classification Search** 422/50, 422/58, 61-63, 67, 68.1, 80, 82.03; 435/817, 435/46, 50, 164, 166, 169, 805, 6; 600/345; 345/824, 156, 158; 455/12.1, 86, 406; 700/17; D10/78, 81, 102, 103, 123, 125, 132; D18/6-8, D18/11-12; D24/224, 232; 73/431, 866.3, 73/499; 204/415, 416, 403.02, 403.06, 409, 204/412, 435; 205/785.5, 787.5, 782

See application file for complete search history.

(57) **CLAIM**

We claim the ornamental design for an analyte test meter, as shown and described.

DESCRIPTION

FIG. 1 is a top perspective view of the analyte test meter, as seen from the top, front and side;

FIG. 2 is a top perspective view of the analyte test meter, as seen from the top, back and side;

FIG. 3 is a top plan view thereof;

FIG. 4 is a bottom plan view thereof;

FIG. 5 is a first side elevational view thereof;

FIG. 6 is a second side elevational view thereof;

FIG. 7 is a front elevational view thereof; and,

FIG. 8 is a rear elevational view thereof.

1 Claim, 6 Drawing Sheets
